BASEBOARD DIFFUSER

Arthur Jon Pulos, East Syracuse, N. Y., and John Raymond Carroll, Urbana, Ill., assignors to Borg-Warner Corporation, a corporation of Illinois

Application June 15, 1956, Serial No. 41,914

Term of patent 14 years

(Cl. D81—21)

We claim:

The ornamental design for a baseboard diffuser, as shown and described.
